UNITED STATES PATENT OFFICE.

EDWARD E. QUIMBY, OF ORANGE, NEW JERSEY, ASSIGNOR TO NATIONAL TUBE COMPANY, OF PITTSBURG, PENNSYLVANIA, A CORPORATION OF NEW JERSEY.

SPRING PULLING-HOOK FOR USE IN BUTT-WELDING.

SPECIFICATION forming part of Letters Patent No. 715,862, dated December 16, 1902.

Application filed October 29, 1901. Renewed July 23, 1902. Serial No. 116,621. (No model.)

To all whom it may concern:

Be it known that I, EDWARD E. QUIMBY, of Orange, New Jersey, have invented a certain new and useful Improvement in Spring Pulling-Hooks for Use in Butt-Welding, of which the following is a specification.

In butt-welding as now practiced when the tube-blank in the form of a flat plate lying in the furnace has been heated to the proper condition the forward end is grasped by the jaws of tongs the reins of which are adapted to extend through a hollow flaring die, called the "welding-bell," and to be connected with a pulling-hook which at the proper time is dropped into engagement with a continuously-running draw-chain. At the instant of such engagement the tongs are subjected to a sudden jerk, which, if the draw-chain is running too rapidly, may cause them to slip their hold on the plate in the furnace or perhaps to break off the front portion of the plate before they can overcome the static inertia of the plate. There is thus imposed upon the draw-chain such a limitation in speed as will insure the continued grasp of the tongs upon the plate at the instant of starting the plate out of the furnace and also at the instant of the first impact of the forward end of the plate against the welding-bell. The pulling-hook heretofore used is a rigid object, and hence at the instant of its engagement with the draw-chain there is a sudden shock administered to the plate which, under present conditions, must be instantly started into motion with a speed corresponding to whatever may be the speed of the draw-chain.

The object of the present invention is to diminish the shock upon the plate or other tube-blank at the instant when the pulling-hook is first engaged with the draw-chain or other drawing mechanism and also to diminish the shock of the impact of the forward end of the blank against the welding-bell.

To that end the invention consists, broadly, of a pulling instrumentality which is extensible and resilient and which is equipped with a stop for so limiting the range of its extensibility that a rigid pull will be exerted upon the tongs during the butt-welding operation.

This broad feature of the invention is susceptible of application to any pulling instrumentality adapted at its rear end to engage the reins of the tongs or like tool and provided at its forward end with suitable means for connection with the draw-chain or other drawing mechanism.

The invention is herein illustrated in connection with an ordinary draw-chain and is shown as a single-pronged pulling-hook provided at its forward end with laterally-projecting wings adapted to travel on the draw-bench on either side of the slot in which the draw-chain moves, and hence susceptible of employment in effecting the disengagement of the hook and draw-chain from each other at the desired stage in the pulling-exursion of the hook, as hereinafter pointed out.

The accompanying drawings of a single-pronged pulling-hook embodying an illustration of the present invention are as follows:

Figure 1 is a side elevation of the pulling-hook, showing a portion of a draw-chain in longitudinal vertical section. Fig. 2 is an elevation of the pronged end of the pulling-hook shown in Fig. 1. Fig. 3 is a transverse vertical section taken through the plane indicated by the dotted line $x-x$ on Fig. 1, showing the ordinary method of construction for enabling the rear end of the hook to engage the reins of the tongs. Fig. 4 is an elevation similar to Fig. 1, but showing the pulling-hook extended in its operative position with its rear end holding the reins of the tongs and its pronged end in engagement with a link of the draw-chain. Fig. 5 is a side elevation of the pronged end of the pulling-hook and the bight of the draw-chain distant from the furnace, showing the manner in which the distant bight of the draw-chain rides clear of the prong a' at the end of the pulling excursion of the hook.

The drawings show a pulling-hook A, approximating the shape of a C-spring. The rear leg A' of the spring is bifurcated, and thus presents the usual channel A² for admitting the reins B of the tongs, which in operation are prevented from dropping out of the channel A² by the bearing of their col-

lars *b* upon the usual inclined offsets *A*³ *A*³. The forward leg *a* of the pulling-hook, which is provided with the usual curved prong *a'*, is also provided with the lateral wings *a*² *a*², which are adapted to bear upon the top of the draw-bench *C* on opposite sides of the slot in which the draw-chain *C'* travels and by such bearing cause the forward bight *C*² of the draw-chain to ride clear of the prong *a'*, as illustrated in Fig. 5, and thus permit the manual removal of the pulling-hook. In operation the legs *A'* and *a* of the pulling-hook are sprung apart by the strain to which they are subjected, and this pulling apart is herein referred to as "extensibility."

The pulling-hook is shaped and proportioned in its cross-section with reference to giving it resilient strength sufficient to enable it to overcome the static inertia of the plate in the furnace and pull the plate forward to the welding-bell. It is preferred that the pull shall be rigid and unyielding after the work has encountered the resistance of the welding-bell, and to that end the pulling-hook is equipped with a suitable tying instrumentality so organized as to limit to a prescribed extent the range of extensibility of the pulling-hook. A simple expedient for the purpose, which is illustrated in the drawings, consists of a tie-bar *D*, loosely inserted through the apertures *d* and *d'* in the legs *A'* and *a* of the pulling-hook. The tie-bar is provided, preferably at its forward end, with the head *D'*, preferably rounded upon its inner side for adapting it to bear upon the forward side of the leg *a*. The rear end portion of the tie-bar is provided with the screw-thread *E* for engaging the jam-nuts *e* *e'*, the nut *e'* being rounded upon its forward side to adapt it to bear upon the rear side of the leg *A'*. The distance between the nut *e'* and the rear side of the leg *A'*, as represented in Fig. 1, determines the range of extensibility of the hook. In Fig. 4 the legs are shown as tied by the bearing of the jam-nut *e'* and the head *D'* against the legs *A'* and *a*, respectively, such being the position assumed during the butt-welding operation.

It will be seen that the features of extensibility and resilience may be employed in the construction of a pulling-hook provided with two prongs, as shown and described in United

States Patent No. 672,914, and that the feature of side wings on the single-pronged hook permits the use of a tripping-switch arranged above the draw-chain for acting like that shown in said Patent No. 672,914 in automatically lifting the pulling-hook from the draw-chain at a predetermined stage in the path of travel of the pulling-hook.

What is claimed as the invention is—

1. In butt-welding apparatus, the combination of the drawing mechanism and pulling-tongs with an extensible and resilient pulling-hook having its rear end adapted for holding the reins of said tongs; its forward end pronged for engaging said drawing mechanism, and provided with a tying instrumentality for limiting its range of extensibility.
2. In butt-welding apparatus, in combination with the drawing mechanism and pulling-tongs, an extensible and resilient pulling-hook having its rear end adapted for holding the reins of said tongs; its forward end pronged for engaging said drawing mechanism and provided with an adjustable tying instrumentality for varying its permitted range of extensibility.
3. In the art of butt-welding, an extensible and resilient pulling-hook adapted at its rear end for holding the reins of the pulling-tongs and provided at its forward end with a single prong and with laterally-projecting wings for bearing upon the top of the draw-bench.
4. In apparatus for butt-welding, the combination of the drawing mechanism and pulling-tongs with an extensible and resilient pulling-hook adapted at its rear end for holding the reins of said tongs and adapted at its front end for engagement with said drawing mechanism.
5. In apparatus for butt-welding, the combination with drawing mechanism, of tongs for engaging the blank to be drawn into tubing, and an extensible and resilient pulling-hook adapted at its rear end for engagement with the tongs and being provided at its forward end with means for engaging the drawing mechanism and with laterally-projecting wings for bearing on the top of the draw-bench.
